UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

MANIFOLDING.

1,273,863.

Specification of Letters Patent. Patented July 30, 1918.

Application filed February 28, 1918. Serial No. 219,184.

To all whom it may concern:

Be it known that I, ARTHUR A. JOHNSON, a citizen of the United States, residing in borough of the Bronx, in the county of the Bronx, city and State of New York, have invented certain new and useful Improvements in Manifolding, of which the following is a specification.

This invention relates to carbon sheets or 10 duplicating material to be used between the work-sheets in manifolding upon a typewriting machine. The invention is especially intended for use in connection with combined typewriting and computing machines which perform addition and subtraction.

It is customary in such machines to use a bichrome ribbon having black and red color-stripes, and to connect the ribbon mechanism to the computing mechanism in such a way that any numbers that are subtracted are typed in red upon the work-sheet; thus the sheet bears its own evidence that such numbers have been subtracted by the computing mechanism.

This expedient, however, has been necessarily limited to the single sheet upon which the ribbon directly prints; and the difficulty has existed that on the carbon copies, which 30 are almost invariably manifolded at the same time as the ribbon copy, there is nothing to indicate whether any particular number has been either added or subtracted by the computing mechanism.

Many efforts have been made to avoid this difficulty and to provide that the several carbon copies shall also indicate for themselves whether any given number appearing thereon has been added or subtracted. For 35 this purpose it has been proposed to have large figure types in the typewriting machine, which are called into use only when subtraction is being performed by the computing mechanism; so that the carbon copies 40 will show by the large figures thereon that certain numbers were subtracted.

It has also been proposed to print a special sign before each number that is to be subtracted, so that the carbon copies shall 50 give evidence accordingly.

It has also been proposed that a special mark shall be printed under each digit that is typed, where such digits are subtracted.

The object of my invention is to provide for a distinction to be made between the 55 added numbers and the subtracted numbers upon the carbon copies of the main or other work-sheet, without necessitating the use of a special set of types, or a special sign or other special device or mechanism in the 60 typewriting machine.

To attain this end, I provide means whereby the numbers that are subtracted are typed in red on the carbon copies, while the remaining numbers and data are typed in 65 black. For this purpose, all numbers that are to be subtracted are typed in a column or columns by themselves as is customary, and the carbon sheet is provided with a vertical stripe of red in register with such subtraction column, so that any numbers written in said column shall appear in red upon the carbon sheet; the remaining portion of the working carbon being black.

For the purpose of keeping the carbon 75 sheet in accurate alinement and register with the work-sheets, so that no numbers shall appear partly in red and partly in black upon the manifold copies, I provide the carbon, preferably upon both edges, 80 with rows of perforations which match the perforations in the work-sheets, and by means of these perforations all of the sheets are impaled upon collating pins usually provided in the typewriting machine. These 85 perforations are made in side margins or borders of the carbon sheets, which are not coated with the carbon or transfer material; and the perforated borders of the carbon sheet may be reinforced, as by folding over 90 the edge, so that the material is of double thickness where the holes are punched through, as conducing to the longevity of the sheet. Since the sheet is usually extremely thin, the extra thickness produced 95 by the fold is not an objection; and the accumulated effect of these reinforcing folds will not prove objectionable in ordinary use, since the extra thickness of the borders of the small number of carbon sheets used in 100 making the few copies customarily made at one writing is not noticeable or objectionable.

In the accompanying drawings,
Figure 1 is a perspective view to illustrate the use of my invention in an Under-

wood typewriting machine provided with a collating device such as illustrated in application No. 117,575, filed August 30, 1916.

Fig. 2 is a view of the improved carbon sheet.

The invention is herein illustrated in connection with one of the more modern methods of mechanical bookkeeping, in which the statement sheet 10 is the sheet on which im-
10 pressions, made by the types 11 through the usual bichrome ribbon having an upper black stripe 12 and a lower red stripe 13, are printed. The imprinted impressions of the types are adapted to be printed on one or
15 more record or inner sheets 14, including a ledger sheet, by means of carbon sheets 15, of which there is one for each inner sheet 14. The statement and record sheets are assembled, usually one by one, upon studs 16 pro-
20 vided on one or both sides of a collating-table 17. The sheets 10 and 14, which, as herein illustrated, extend entirely across the table, usually have perforations 18 along one or both sides to fit upon the studs 16,
25 the provision of the studs and perforations being adapted not only to aline the sheets in the desired registration, but also permitting the sheets to be assembled in different relationships when required, in a manner
30 well understood by those skilled in the art.

In the form of the invention, as herein disclosed, the carbon sheet 15 has an uncolored portion 19 or margin at one or both sides, said margin being preferably strength-
35 ened by a reinforcing strip 20 which may be a strip of the uncoated carbon paper folded over.

The statement sheet 10, as herein shown, has a number of columns 21 on which digits
40 are usually written in black, and two columns 22 on which the digits are usually written in red. To enable the red digits of the statement sheet 10 to be imprinted in red on the ledger sheet 14, the black or other staple color of carbon sheet 15 is provided
45 with a red or other contrasting stripe 23 which is of the same width as the two columns 22, and is adapted to be accurately brought beneath said columns, because the
50 carbon sheet 15 is provided with perforations 24 in its strengthened margin, so located that when the statement sheet 10 is positioned by fitting its perforations 18 over the studs 16, the two columns 22 thereof will
55 fall precisely over the red stripe 23 of the carbon sheet when that sheet is alined by fitting its perforations 24 over the studs 16.

Since the statement sheet has several columns 21 to the left of the red digit columns
60 22 and a single or "old balance" column 21 to the right of the red digit columns 22, the carbon sheet is provided with a broad black stripe 25 adapted to coincide with the left-hand columns 21 of the ledger, when the
65 sheets are alined as aforesaid, and with a

narrow right-hand black stripe 26, which is adapted at the same time to coincide with the right-hand black digit column 21. Thus, the red stripe 23 on the carbon sheet is between a large broader black stripe of the 70 carbon sheet and a narrower black stripe.

When the sheets have been alined by the studs 16, the feed rolls 27 may be thrown on to clamp the sheets to the platen, superposed as they are upon each other, and then 75 the handle 28 may be operated to withdraw the studs 16 from the perforations.

All of the sheets are fed, line by line, around the platen in the usual manner, as the writing proceeds, the machine being provided with the bichrome ribbon 12, 13, which may automatically type all of the added numbers in black, as well as the miscellaneous data that relates to such numbers, and may also type the subtracted numbers 85 in red.

Hence, when the typing is finished, both the outer and inner work-sheets show the added numbers in black and the subtracted numbers in red. The carbon sheet is preferably provided with a designation "Top" 90 at one end 29, so that the operator will not, by mistake, place the other end up and thereby bring the red stripe out of register with the corresponding columns on the work-sheets. 95

For the purpose of making the alinement very exact, the statement sheet is frequently made in the form herein illustrated, with perforations 18 at each margin thereof. In 100 order to enable the statement sheet to be sent to the customer without the stud-fitting perforations 18, which are somewhat unsightly to the customer, the statement sheet is usually provided with a row of fine perforations 30, at each side, so that the edges 31 of the statement in which the large perforations 18 are formed, may be entirely torn off before mailing the sheet. The right-hand row of fine perforations 30 is usually 110 placed between the right-hand column 22 and the right-hand column 21, so that when the right-hand edge 31 is torn off, the right-hand or "old balance" column 21 will be torn off therewith. The sheets are usually 115 made to have this column torn off, because that column is frequently misleading to the customer, and is usually a mere incident to the system of bookkeeping used.

Variations may be resorted to within the 120 scope of the invention, and portions of the improvements may be used without others.

Having thus described my invention, I claim:

1. A carbon-paper sheet adapted to co-
125 operate with an original sheet on which typewriting is done in black in a plurality of columns, and in a less number of columns in red, said carbon sheet comprising a nar-
row red stripe to correspond to a red orig- 130

inal column, and a wide black stripe to correspond to a plurality of black columns.

2. A carbon-paper sheet adapted to coöperate with an original sheet on which

5 typewriting is done in black in a plurality of columns, and in a less number of columns in red, said carbon-sheet comprising a narrow red stripe to correspond to a red original column, and a wide black stripe to correspond to a plurality of black columns, and another black stripe corresponding to a non-adjacent column, said stripe so arranged that the two black stripes lie on the opposite sides of the red stripe.

10 3. The combination with a perforated original sheet adapted to be written upon in several columns in more than one color, of a perforated carbon-sheet having a black stripe thereon adapted to coincide with a plurality of columns in the original sheet, both sets of perforations adapted to fit a single set of pins, and a narrower red stripe thereon adapted to coincide with another column, said pins alining said two sheets so

15 25 that the red stripe will coincide with a column on the original sheet, each sheet also comprising a plurality of perforations at the opposite edge thereof adapted to fit over another set of alining pins.

30 4. The combination with an original sheet adapted to be written upon in several columns in more than one color, of a carbon-sheet having a black stripe thereon adapted to coincide with a plurality of columns in the original sheet, a narrower red stripe thereon adapted to fit over another column, a plurality of perforations in said original sheet adapted to fit studs to aline the original sheet, a reinforcement for the edge of the carbon-sheet, and a plurality of perforations on said edge of said carbon-sheet adapted to fit over said studs to cause a certain column on the original sheet to coincide with the red column on the carbon-sheet, each sheet also comprising a plurality of perforations at the opposite edge thereof adapted to fit over another set of alining studs.

45 5. The combination with an original sheet and a record sheet adapted to receive a carbon copy of the original sheet, of rulings in vertical columns on said original sheet, and a carbon-sheet adapted to be alined with said original sheet, said carbon-sheet comprising a red stripe which will coincide with a certain column with said original sheet when the sheets are alined, a black stripe on each side of said red stripe, adapted to coincide with other columns of said original sheet, with the result that characters printed on the original sheet in red over a red column of the carbon-sheet will be printed on

the record sheet in red by the red carbon, and that characters printed in black on the original sheet will be printed by the carbon- sheet in black on the record sheet.

6. A carbon-paper sheet adapted to coöperate with an original sheet on which typewriting is done in black in a plurality of columns, and in a less number of columns in red at one side of the black columns, and also in black on the opposite side of the red, said original sheet comprising perforations adapted to fit over alining studs, said carbon-sheet comprising a narrow red stripe to correspond to a red original column, a black wide stripe to correspond to a plurality of black columns, a narrow black stripe to correspond to the other black columns, and a reinforcing edge for said carbon-sheet comprising perforations adapted to fit over the same alining studs.

7. A carbon-paper sheet adapted to coöperate with an original sheet on which typewriting is done in black in a plurality of columns, and in a less number of columns in red at one side of the black columns, and also in black on the opposite side of the red, said original sheet comprising perforations adapted to fit over alining studs, said carbon-sheet comprising a narrow red stripe to correspond to a red original column, a black wide stripe to correspond to a plurality of black columns, a narrow black stripe to correspond to the other black columns, a reinforcing edge along each side of said carbon-sheet comprising perforations adapted to fit over alining studs, and a sign imprinted on said carbon-sheet, at one end thereof, adapted to indicate which end is adapted to be first inserted into the typewriting machine.

8. A carbon-paper sheet adapted to coöperate with an original sheet on which typewriting is done in black in a plurality of columns, and in a less number of columns in red at one side of the black columns, said original sheet comprising perforations adapted to fit over alining studs, said carbon-sheet comprising a narrow red stripe to correspond to a red original column, a black wide stripe to correspond to a plurality of black columns, a reinforcing edge for said carbon-sheet comprising perforations adapted to fit over the same alining studs, and a sign imprinted on said carbon-sheet, at one end thereof, adapted to indicate which end is adapted to be first inserted into the typewriting machine.

ARTHUR A. JOHNSON.
